UNITED STATES PATENT OFFICE.

LAWRENCE GIVULINOVICH, OF SEATTLE, WASHINGTON.

BUTTER-CUTTING MACHINE.

1,111,373.

Specification of Letters Patent. Patented Sept. 22, 1914.

Application filed February 28, 1914. Serial No. 821,717.

To all whom it may concern:

Be it known that I, LAWRENCE GIVULINOVICH, a citizen of the United States, residing at Seattle, in the county of King and State 5 of Washington, have invented certain new and useful Improvements in Butter-Cutting Machines; and I do hereby declare the following to be a full, clear, and exact description of the invention, such as will enable others skilled in the art to which it 10 pertains to make and use the same.

This invention relates to cutters, and is more particularly adapted for use in hotels, restaurants, etc., for cutting blocks of butter, 15 and has for one of its objects the provision of means for cutting butter into blocks of any desired size.

Another object of this invention resides in the provision of means for maintaining 20 the cutting members at any desired degree of tension.

A further object of this invention resides in the provision of means for resiliently 25 mounting the cutting members for preventing a rupture or breakage of the same.

A still further object of this invention resides in the construction of the cutting members and the mounting therefor, whereby the 30 same may be readily attached or detached for the insertion of a greater number of the cutting members, or the withdrawal of the same also, if desired, and,

Another object of this invention resides in the provision of means for increasing or 35 decreasing the space between the parallel cutting members.

These and other objects will more fully appear and the nature of the invention more clearly understood by the construction, combination and arrangement of parts thereof 40 as described in the following specification, defined in the appended claims and illustrated in the accompanying drawings, in which,

Figure 1 is a top plan view of my device in its complete form, ready for use, Fig. 2 is a front view of the same showing the mounting of the handles thereon for operating the same; Fig. 3 is a top view of a part of the 50 front portion of my device, with one of the

channel lids removed, showing the interior construction of the mounting of the cutting members within the channel bars, Fig. 4 is an end elevation, partly in section, taken on line 4-4 of Fig. 1; Fig. 5 is an end elevation of the same, taken on line 5-5 of Fig. 1, and, Fig. 6 is a fragmentary detail view illustrating the positions of adjustment of the cutting members.

Like reference characters denote similar parts through the several views of the drawings, and reference being had to the same, 1 denotes the base having mounted thereon the elevated platform 2, upon which the objects to be cut are positioned. At the forward portion of the base 1 and arranged upon the same, is the channel bar 3, provided at each of its ends with the post 4. Upon the channel bar 3 is mounted a channel cover plate 5, the ends of which are cut 65 away to form the laps 6 for resting upon the top of the posts 4.

At the front of the base 1 is arranged the handle 8, and also upon the front of the channel bar 3 is arranged the handle 9, 75 above and in proximity with the handle 8, these handles being designed for operating the cutting frame and the base relative to each other, and at the same time to furnish means for conveniently carrying the device, 80 when it is desired to transfer the same from one point to another.

Arranged at the rear end of the base 1 is also a similar channel bar 10, provided with the end posts 11, and upon the channel bar 85 10 is arranged a similar channel cover plate 12, also being cut away to provide laps 13 for engaging the top of the posts 11.

For retaining the plates 5 upon channel bar 3 are the thumb nuts 14 passing through 90 the laps 6 of the cover 5 and engaging the vertically disposed internal screw threads 14' of the post 6. The channel bar 10 and the rear portion of the base 1 are connected together through the medium of the hinges 95 15, and for retaining the plate 12 upon the bar 10 thereat are the thumb screws 15', engaging the posts 11 of the channel bar 10 in a similar manner as the plate 5 is retained on the channel bar 3.

For connecting the bars 3 and 10 together and for adjusting the same relative to each other, is provided the upper rods 16 and 17 oppositely disposed at the respective sides 5 of the device, each being provided at the front end with screw threads for engaging transversely arranged screw threads within the posts 4 of the bar 3, and the opposite ends of the respective rods being rotatable 10 within the posts 11 of the bar 10, as shown at 17'. The rods 16 and 17 are rotated by the thumb nuts 18 and 19, respectively, fixedly mounted upon the ends of the rods. Arranged beneath the rods 16 and 17 are 15 the similar rods 20 and 21, these rods being positioned in opposed relation to the rods 16 and 17, the rods 20 and 21 being designed to engage transverse internal screw threads 20' in the posts 11 of the bar 10 and having 20 their opposite ends rotatably mounted in the posts 4 of the bar 3, as shown at 21', and for rotating the rods 20 and 21 are the thumb nuts 22 and 23, fixedly connected to the rods 20 and 21, respectively. 25 Horizontally disposed within the device and extending from the channel bar 3 to the channel bar 10, are the parallel and equi-spaced cutters 25, and arranged transversely to the cutters 25 is the second cutter 26, arranged beneath the cutters 25 and having one of its ends fixedly connected to the plate 27 extending in vertical direction and having its ends embracing the rods 17 and 21, respectively. The opposite end of the cutter 26 being attached to the eye 28 of the bolt 29, the bolt projecting through the plate 30, similarly arranged upon the rods 16 and 20 in the manner of the plate 27, and for controlling the tension of the cutter 26 30 is the thumb nut 31, engaging the threads of the bolt 29 at the outer side of the plate 30. Any desired number of cutters 26 may be used.

Arranged longitudinally within each of the bars 3 and 10 and extending longitudinally therein, is the rod 32, the ends of the same being rotatably mounted within the respective posts of the bars, as at 32', see Fig. 3, one end of the bar 32 projecting outwardly through one of the posts of the channel bars and having fixedly secured thereto the thumb nut 33 for rotating the same, and upon the opposite end of the rod 32 are the screw threads 34, upon which is 55 adapted to travel the adjusting nut 35.

Interposed between one of the posts of the channel bars and the traveling nut 35 is the elongated coiled spring 36, the spring surrounding the rod 32, and to the coils are 60 connected the cutters 25 through the medium of the hooks 37 arranged at each of the ends of the cutters 25.

The operation of my device will be ap-

parent from the following advantages herein enumerated, it being obvious that when 65 a print of butter, or other object to be cut, is placed upon platform 2, the cutting frame being thrown rearwardly upon the hinges 15, it is only necessary to grasp the handle 9' of the cutting frame and pull the same 70 forwardly and downwardly, whereby the cutters 25 and 26 will pass through the article until the same rest upon the upper surface of the platform 2, and after this 75 operation it will not be necessary, unless desired, to return the cutting frame to its rearward position, as the blocks of the article cut may be removed readily therefrom.

The cutters 25 are resiliently mounted within the device, the ends of the same being attached to the coils of the springs 36, and any number of these cutters may be used to meet the requirements of the user, and it is clearly obvious that by rotating the thumb nuts 18, 19, 22 and 23, the adjusting rods 16, 17, 20 and 21 will cause the channel bar 3 to move in the direction of the bar 10, which movement will cause the cutters 25 to sufficiently slacken in order that the hook ends 37 may be detached 90 from the coils of the spring 36 for removing the cutters therefrom, or the operation may be reversed when it is desired to insert additional cutters. The space between the parallel cutters 25 is also controlled by the 95 rotation of the rod 32, which rotation will cause the traveling nut 35 to move upon the threads of the rod 32, according to the direction of rotation of the rod. The respective travel of the nut 35 controls the 100 space between the coils of the springs, and consequently, the cutters 25 are brought closer together or further apart in accordance with the direction of travel of the traveling nut 35 within the channel bars. The 105 tension of the cutters 25 is obviously controlled by the rotation of the rods at the sides of the device for connecting the respective channel bars.

Having thus described my invention, 110 what I claim as new and desire to secure by Letters-Patent of the United States is,

1. In a device of the class described, comprising a base, a platform arranged upon said base, a frame hingedly connected to 115 said base and surrounding said platform, means for operating said frame, a series of cutters supported within said frame, means upon said frame for adjusting the tension of said cutters, and means for yieldably supporting said cutters.

2. In a device of the class described, comprising a base, a platform arranged upon said base, a frame hingedly connected to 120 said base and surrounding said platform, means for operating said frame.

a series of parallel and equi-spaced cutters supported within said frame, means upon said frame for adjusting the tension of said cutters, means for yieldably supporting said cutters, and means for adjusting the yieldably supporting means for determining the degree of space between said cutters.

In testimony whereof I have signed my name to this specification in the presence of 10 two subscribing witnesses.

LAWRENCE GIVULINOVICH.
